ROADWAY MARKER

Peter Hedgewick, Windsor, Ontario, Canada, assignor to
Reflex Corporation of Canada Limited, Amherstburg,
Ontario, Canada, a corporation of Canada

Filed Sept. 13, 1968, Ser. No. 13,524

Term of patent 14 years

Int. Cl. D29—99

U.S. Cl. D72—1

FIG. 1 is a perspective view of the roadway marker, five additional markers and the roadway being shown in broken lines for illustrative purposes only.

FIG. 2 is a plan view of the roadway marker, the reflecting elements in the outer circumferential area being conventionally represented for convenience of illustration, said elements being accurately shown in FIGURE 6.

FIG. 3 is a transverse sectional view of the same.

FIG. 4 is a fragmentary sectional view on an enlarged scale taken in the direction of the arrow 4 in FIG. 3.

FIG. 5 is a fragmentary view on a greatly enlarged scale of a portion of the roadway marker shown in FIG. 3.

FIG. 6 is a fragmentary view on an enlarged scale taken in the direction of the arrow 6 in FIG. 3.

I claim:

The ornamental design for a roadway marker, as shown and described.
